UNITED STATES PATENT OFFICE.

JAMES F. McELROY, OF ALBANY, NEW YORK, ASSIGNOR TO CONSOLIDATED CAR-HEATING COMPANY, A CORPORATION OF WEST VIRGINIA.

THERMOSTATIC VALVE.

1,121,591.

Specification of Letters Patent.

Patented Dec. 15, 1914.

Application filed May 27, 1910. Serial No. 563,808.

Third claim it may concern:

Be it known that I, JAMES F. McELROY, a citizen of the United States, residing at Albany, county of Albany, State of New York, 5 have invented certain new and useful Improvements in Thermostatic Valves, the following being a full, clear, and exact disclosure of the one form of my invention which at present deem preferable.

For a detailed description of the present 10 form of my invention, reference may be had to the following specification and to the accompanying drawings, which illustrate my invention.

Figure 1 is a side view of my device applied to the thermostatic control of the admission of steam to the heating apparatus of a railway car; Fig. 2 is a front elevation of Fig. 1; Fig. 3 is a side elevation of the magnet and intermediate operating connections between it and the valve; Fig. 4 is a view, partly in section, of the opposite side of the apparatus shown in Fig. 3; Fig. 5 is a diagram of the electrical circuits; Figs. 6, 7, 8 and 9 show details.

My invention relates to an arrangement for the operation of a valve by means of an electromagnet under the automatic control of a thermostat. It is particularly intended 30 for the operation of the steam inlet valve of a steam heating apparatus on a railway car.

Turning to Fig. 1, A represents a train pipe of a steam system, O being the ingoing and N the outgoing pipes of the radiator system on the car. Between the train pipe A and the aforesaid pipes N and O is a control valve such as is ordinarily employed in my train heating system, R being the controlling thermostat for the steam trap, M being the cut-off hand valve, and L a valve for converting the system to either the low-pressure or high-pressure type. Between pipe A and the valve K is a valve chest B containing the secondary cut-off valve which it is the purpose of my invention to operate under automatic thermostatic control by means of a magnet.

Turning to Fig. 3 there is shown near the bottom of the figure a section of the aforesaid valve chest B, wherein the upper and lower portions thereof are shown as separated by a partition *b* in which is fixed the valve seat *w*. W is the valve adapted to fit down upon the seat *w* to cut-off the flow of

steam from the train pipe but represented as elevated into the position shown to permit of the flow of the steam through the valve chest B. C is a vertical operating rod containing a ball joint *c* and extending upward from the valve W through the casting D to the operating mechanism to be hereinafter described.

As appears in Fig. 1 the valve W is below the floor P of the car and so subjected to the external temperature. The horizontal floor P of the car serves as a support for the electromagnetic mechanism to which I will next call attention.

Turning to Figs. 3 and 4, 2 represents the external iron casing of a horizontal and horizontally-acting solenoid magnet comprising the coils 200 and 300 and the movable magnetic core 3. The core 3 in Fig. 4 is in the position which it will assume when the coil 300 is energized, whereas when coil 200 is energized it will be drawn toward the right in the same position relative to coil 200 which it now occupies with relation to the coil 300. An angle lever E is pivotally connected to the magnet support or base, as indicated at *e*, said lever being provided with upright and horizontal branches. The upright branch of this lever is normally drawn forward by means of a spring H, one end of which engages the lever and the other end 85 engages an offset on the sleeve J which is adjustably mounted on the end of a short rod projecting forward from the casing 2. The horizontal branch of the angle lever E is jointed to the upper end of the vertical 90 operating rod C. F represents a cam on the short shaft *f* which is rotated by the lever G that has its outer end pivotally connected to the extremity of the core stem 3^a. The roller Q, journaled on the horizontal 95 branch of angle lever E, is arranged to ride on the periphery of the cam F, as particularly appears in Figs. 3, 6 and 9. When the coil 300 is energized and the core 3 drawn forward, the aforesaid lever G will be 100 turned to the position shown in Fig. 3. This will rotate cam F and the wheel Q will ride up the plane face of the cam and the lever E thereby raised, together with the operating rods jointed to the end of the lever.

105 This will open the valve and admit steam. When the magnet 200 is energized and the core 3 drawn rearward, then the stem 3^a will

turn the lever G to the left until it comes to the position shown in Fig. 5. This action will first lift the lever E slightly and then allow it to drop, the wheel Q traveling down the plane face of the case.

It therefore appears that the valve will be opened or closed according as the coil 300 or the coil 200 of the two-coil solenoid magnet is energized, and the magnet is therefore so constituted that its core will be operated and remain set in the position to which it has been brought by the energizing of one or the other of the coils 200 or 300. To identify this feature, the magnet may be termed a two-throw magnet.

Turning to Fig. 3, which shows the electric circuits, it will be observed that there are two distinct circuits, one marked 20 containing coil 200 and the other marked 30, containing coil 300. A third circuit marked 10 starts from the tongue 1 of the thermostat and after passing through the battery, or source of current 50, it goes to the transfer switch to be hereinafter described, by means of which it is connected either to the aforesaid circuit 20 or to the aforesaid circuit 30. The circuit 20 at the thermostat passes through a retaining magnet 6 and terminates at the right-hand contact for the thermostat tongue 1. The other circuit 30 passes through a similar retaining magnet 5 and terminates at the left-hand contact for the thermostatic tongue. The thermostatic tongue 1 is adapted to play between the aforesaid contacts and to engage one or the other according to the temperature, and so energizes one or the other of the circuits 20 and 30 and the magnets 200 and 300 contained therein respectively.

The aforesaid transfer switch is mounted on the cam shaft and rotates therein as particularly appears in Figs. 4, 5, 6 and 7. Turning to Fig. 6, 42 is an insulating plug forming a continuation of the cam shaft 7 and carrying a short metal sleeve 41, which is perforated transversely and contains in the perforation a freely moving ball of copper 43. The sleeve 41 also passes through a vertical insulating plate 40, having an opening therein on opposite sides of which, on the front of the plate, are two contacts 21 and 31, the former serving as one terminal of the aforesaid circuit 20 and the other as one terminal of the aforesaid circuit 30. On the rear of the plate are two similar contacts of which one, to-wit, the one marked 101, is shown in Fig. 7, the other one being similarly placed on the diametrically opposite side of the opening in the insulating plate 40. Both of these rear contacts form one terminal of the aforesaid circuit 10. As the aforesaid cam shaft 7 is rotated back and forth by the action of the magnet, ball 43 is caused to roll through the sleeve from one side to the other to put the

rear contact in electrical connection with either the contact 21 or the contact 31 and thereby put the circuit 10 itself in electrical connection with either the circuit 20 or the circuit 30. This switch I forms a transfer switch, because it serves to transfer the connection of circuit 10 to one or the other of the thermostat circuits 30 and 20. Thus if the thermostat tongue 1 is moved to the right to close the circuit 20, that circuit will be found to be connected to the circuit 10, so that the current in battery 50 will find a closed path through the circuits 10 and 20 which will include the operating coil 200. This will operate the core of the solenoid to allow the valve W to close and will at the same time operate the transfer switch to break the connection with the said circuit 20 and close the connection with the opposite circuit 30, so that the latter will be in condition to act when the thermostat moves in the opposite direction to admit current to circuit 30 and the opposite coil 300. The advantage of the ball form of switch is that the connection will be maintained for a sufficient length of time on one side, the ball remaining in contact with the circuit terminals on that side until the movement of the apparatus is completed and the motion stops; then the ball will roll across by gravity to the opposite side and close the connection between the contacts there. The ball maintains three points of contact in either extreme position, one point being on the metallic holder of the ball and the other two on the respective contacts supported on the fiber piece 40. The quick motion of the rocking cam shaft will cause the ball to roll along the circular contacts with which it engages until the machine stops and then gravity will cause the ball to roll away to its opposite position. This insures a circuit through the acting solenoid coil which remains intact until the motion of the part ceases. The ball then breaks that circuit and establishes a circuit for the opposite solenoid. The ball is free from liability to stick and if made of copper about three-fourths of an inch in diameter, has sufficient weight to make and maintain a good contact, the contact surfaces on the ball being always fresh.

The tension on the spring H is adjustable and is made sufficient to close the steam valve W against the highest train pipe pressure—say one hundred pounds. In this connection it will be noted that when the parts are in the position illustrated in Fig. 3, the cam F is of such shape that the roller O rests upon the rounded face, thereby holding the valve open without any current being maintained in the coils of the magnet. When the parts are in the position shown in Fig. 9, with the valve closed, the tension of the spring H is thrown upon the valve to seat

the latter and hold it seated against the steam pressure. Thus no current in the magnet is necessary to hold the valve closed. The cam is thus a non-reacting operating connection between the magnet on the one hand and the valve operating member formed by the lever E on the other hand, and when operated by the magnet the cam is not responsive to the counter pull of the 10 spring H on member E. Only when the cam is reversed by the action of the opposite magnet coil 200 will the spring H be permitted to act and close the valve against the force of the fluid pressure which tends to 15 open it.

What I claim as new and desire to secure by Letters Patent is:

1. In a valve operating mechanism, the combination with a valve, of a two-throw magnet, a lever pivotally connected to and a cam operated by said lever, a circuit closer for said magnet including a contact carried by said cam, and means actuated by said cam for operating said valve.

2. In a valve operating mechanism, the combination with a valve, of a two-throw magnet, an operating lever for said valve, a crank lever pivotally connected with said magnet, a circuit closer for said magnet including a contact carried by said crank lever, and means actuated by said crank lever for operating said valve.

3. In a valve operating mechanism, the combination with a valve, of a two-throw magnet, a crank lever pivotally connected to and operated by said magnet, a cam operated by said lever, a circuit closer for said magnet including a contact carried by said cam, and means actuated by said cam for operating said valve.

4. In a valve operating mechanism the combination with a two-throw magnet and a horizontal support therefor, of a valve casing below said support, a pendent tubular connection between said valve casing and said support, a valve operating device slideable in said tubular connection, and means connected with said magnet for actuating said valve operating device.

5. In a valve operating mechanism the combination with a two-throw magnet and a horizontal support therefor, of a valve casing below said support, a tubular connection between said valve casing and said support, a valve operating device slideable in said tubular connection, and a cam connected with said magnet for actuating said valve operating device.

6. In a valve operating mechanism the combination with a two-throw magnet and a horizontal support therefor, of a valve casing below said support, a tubular connection between said valve casing and said support, a valve operating device in said tubular connection, a crank lever connected with

said magnet, and a cam carried by said crank lever for actuating said valve operating device.

7. In a valve operating mechanism the combination with a two-throw magnet and a horizontal support therefor, of a valve casing below said support, a tubular connection between said valve casing and said support, a valve operating device in said tubular connection, a cam connected with said magnet for actuating said valve operating device, and a circuit closer for said magnet including a contact carried by said cam.

8. In a valve operating mechanism the combination with a two-throw magnet and a horizontal support therefor, of a valve casing below said support, a tubular connection between said valve casing and said support, a valve operating device in said tubular connection, a crank lever connected with said magnet and provided with a cam for actuating said valve operating device, and a circuit closer for said magnet including a contact carried by said crank lever.

9. In a valve operating mechanism the combination with a valve, of a magnet, a cam operatively connected with said magnet, a circuit closer for said magnet including a contact carried by said cam, and a crank lever connected with said valve and normally engaging said cam.

10. In a valve operating mechanism the combination with a valve, of a magnet, a cam operatively connected with said magnet, a circuit closer for said magnet including a contact carried by said cam, a crank lever for operating said valve, a spring for holding said lever normally in engagement with said cam, and means for adjusting the tension of said spring.

11. In a valve operating mechanism, the combination with a valve, of a two-throw magnet, a crank lever connected therewith, means actuated by said crank lever for operating said valve, and a transfer switch carried by the crank lever and comprising oppositely disposed stationary contacts, a sleeve, and a gravity contact carried by and movable transversely of said sleeve.

12. In a valve operating mechanism, the combination with a valve, of a two-throw magnet, a crank lever connected therewith, means actuated by said crank lever for operating said valve, and a transfer switch comprising a metal sleeve supported by said crank lever and insulated therefrom, oppositely disposed stationary contacts and a gravity contact carried by said sleeve.

13. In a valve operating mechanism, the combination with a valve, of a two-throw magnet, a crank lever connected therewith, means actuated by said crank lever for operating said valve, and a transfer switch comprising an oppositely disposed stationary contact, a sleeve, and a metal ball form-

- ing a gravity contact and loosely mounted in and movable transversely of said sleeve.
12. In a valve operating mechanism, the combination with a valve, of a two-throw magnet, a crank lever connected therewith, means actuated by said crank lever for operating said valve, automatically acting means controlling the magnet and a transfer switch comprising a metal sleeve carried by said crank lever and insulated therefrom, said sleeve being provided with a transverse opening, oppositely disposed stationary contacts, and a metal ball forming a gravity contact and mounted to reciprocate in the transverse opening of said sleeve.
13. In a valve operating mechanism, the combination with a valve, of a two-throw magnet, two circuits for the magnet, a thermostat controlling said circuits, controlling magnets for the thermostats included in the respective circuits, a cam operatively connected with said magnet, means actuated by said cam for operating said valve, and a transfer switch including a contact connected with said cam.
14. In a valve operating mechanism, the combination with a valve, of a two-throw magnet, two circuits for the magnet, a thermostat controlling said circuits, controlling magnets for said thermostats included in the respective circuits, a cam operatively connected with said magnet, means actuated by said cam for operating said valve, and a transfer switch for said circuits including a metal ball forming a gravity contact and controlled by said cam.
15. In a valve operating mechanism, the combination with a valve, a rotatable cam shaft provided with a cam and a crank arm, an operating lever for said valve extending transversely of said cam shaft and resting upon said cam, and a magnet having its core mounted to reciprocate across said cam shaft and having one end connected with the free end of said crank arm.
16. In a valve operating mechanism, the combination with a valve, of a two-throw magnet, two circuits for the magnet, a thermostat controlling said circuits, controlling magnets for said thermostats included in the respective circuits, a cam operatively connected with said magnet, means actuated by said cam for operating said valve, and a transfer switch for said circuits including a metal ball forming a gravity contact and controlled by said cam.
17. In a valve operating mechanism, the combination with a valve, a rotatable cam shaft provided with a cam and a crank arm, an operating lever for said valve extending transversely of said cam shaft and resting upon said cam, and a magnet having its core mounted to reciprocate across said cam shaft and having one end connected with the free end of said crank arm.
18. In a valve operating mechanism, the combination with a valve, a rotatable cam shaft provided with a cam and a crank arm, a bell crank lever having one arm extending transversely of said cam shaft and resting upon said cam, said arm being connected with said valve, a spring connected to the other arm of said bell crank lever, and a magnet having its core mounted to reciprocate across said cam shaft and having its end connected with the free end of said crank arm.
19. The combination with a valve and mechanism for operating the same, of a magnet, a lever operated by the magnet, a cam actuated by said lever for operating said mechanism in one direction, adjustable
- means independent of the magnet for operating the mechanism in an opposite direction, and automatically acting means for controlling the magnet.
20. In a valve operating mechanism, the combination with a valve, a rotatable cam shaft provided with a cam and a crank arm, an operating lever for said valve extending transversely of said cam shaft and resting upon said cam, and a magnet having its core mounted to reciprocate across said cam shaft and having one end connected with the free end of said crank arm, said cam being provided with means for retaining said valve in its shifted position when the magnet is dead.
21. In a valve operating mechanism, the combination with a valve, a rotatable cam shaft provided with a cam and a crank arm, a bell crank lever having one arm extending transversely of said cam shaft and resting upon said cam, said arm being connected with said valve, a spring connected to the other arm of said bell crank lever, a magnet having its core mounted to reciprocate across said cam shaft and having its end connected with the free end of said crank arm, and means for adjusting the tension of said spring.
22. In a valve operating device the combination with a valve, of a support, a magnet carried thereby, an angular lever pivoted to the support for operating the valve, a roller carried by the lever, a crank lever carried by the support and having one end pivoted to the stem of the magnet, a cam carried by the crank lever and engaging said roller, a spring connection between one end of the angular lever and the support, and means for controlling the operation of the magnet.
23. In a valve operating mechanism, the combination with a valve, a rotatable cam shaft provided with a cam and a crank arm, a bell crank lever having one arm extending transversely of said cam shaft and resting upon said cam, said arm being connected with said valve, a spring connected to the other arm of said bell crank lever, a magnet having its core mounted to reciprocate across said cam shaft and having its end connected with the free end of said crank arm, said cam being so shaped as to be non-responsive to the action of said spring.

In witness whereof I have hereunto set my hand, before two subscribing witnesses, this 24th day of May, 1910.

JAMES F. McELROY.
